UNITED STATES PATENT OFFICE.

OTTO L. BIHLMIRE, OF BARODA, MICHIGAN, ASSIGNOR, BY MESNE ASSIGNMENTS, TO
GIDELITE MFG. CO., OF CHICAGO, ILLINOIS, A CORPORATION OF ILLINOIS.

DESIGN FOR AN AUTOMOBILE RADIATOR CAP.

Application filed September 11, 1922. Serial No. 3,673. Term of patent 14 years.

To all whom it may concern:

Be it known that I, OTTO L. BIHLMIRE, a citizen of the United States, residing at Baroda, in the county of Berrien and State of Michigan, have invented a new, original, and ornamental Design for Automobile Radiator Caps, of which the following is a specification, reference being had to the accompanying drawing, forming part thereof.

Figure 1 is a rear view of same.

Figure 2 is a side view of the same.

I claim:

The ornamental design for an automobile radiator cap substantially as shown.

OTTO L. BIHLMIRE.
